(57) **CLAIM**

The ornamental design for an operating light, as shown and described.

DESCRIPTION

FIG. 1 is a bottom perspective view of an operating light according to the claimed design;

FIG. 2 is a top perspective view of the operating light; and, FIG. 3 is a front perspective view of the operating light. The broken lines illustrate variations of unclaimed features of the operating light and form no part of the claimed design.

1 Claim, 3 Drawing Sheets
